C. W. PAGE

DOOR OPERATING MECHANISM

Filed Oct. 10, 1922

UNITED STATES PATENT OFFICE.

CHARLES W. PAGE, OF CATHLAMET, WASHINGTON.

DOOR-OPERATING MECHANISM.

Application filed October 10, 1922. Serial No. 593,634.

To all whom it may concern:

Be it known that I, CHARLES W. PAGE, a citizen of the United States, residing at Cathlamet, in the county of Wahkiakum 5 and State of Washington, have invented new and useful Improvements in Door-Operating Mechanisms, of which the following is a specification.

This invention relates to mechanism for 10 operating doors, and more particularly the doors of automobiles and other motor vehicles, the object of the invention being to provide a simple and efficient means which automatically throws open the door when 15 the latch thereof is retracted.

With the object stated in view, the invention consists in a novel combination and arrangement of parts to be hereinafter described and claimed, and in order that the 20 same may be better understood, reference is had to the accompanying drawing, wherein

Figure 1 is an elevation of the door viewed from the inside of the car; Fig. 2 is an enlarged fragment of the door with parts 25 broken away to show the latch, and Figs. 3 and 4 are sections on the lines 3-3, and 4-4, respectively, of Fig. 2.

Referring specifically to the drawing, 5 denotes the side of the car body to which 30 the door 6 is applied. The edge of the door opening has a keeper recess 7 for a slidable latch bolt 8 carried by the door. This latch bolt is mounted in a housing 9 between 35 guide ribs 10 therein, and it is backed by a spring 11 which constantly urges it forwardly.

The latch bolt 8 is provided with two 40 separate operating means. One of these means is a hand lever 12 fulcrumed at 13 in the housing 9 and projecting at one end from the top edge of the door, its other end seating in a notch 14 in the top edge of the bolt. The door and the bolt housing are 45 suitably apertured at the top so that the lever may protrude from the top edge of the door. The other latch-operating means is a lever 15 fulcrumed at 16 in the housing 9. One end of this lever seats in a recess 17 in the side of the bolt, and its other end has a 50 laterally extending foot piece 18 which pro-

jects through a curved slot 19 in the door so that it is located alongside the inner face of the door for operation by the car-occupant's foot.

It will be evident from the foregoing that 55 the door latch bolt 8 may be retracted by either the hand-operated lever 12 or the foot-operated lever 15.

When the latch bolt 8 has been retracted to release the door 6, the latter is automatically thrown open by a spring-backed push button 20, the spring thereof being shown at 21. This button and its spring are enclosed in a housing 22 mounted on the outer face of the door 6 in such a position that 60 the button may bear against the outer face of the car body 5 close to the door-opening, the housing having an aperture through which the button protrudes.

When the door 6 is closed, the spring 21 70 is compressed as the button 20 contacts with the car body 5 and is thereby pushed back into the housing 22. It will, therefore, be evident that when the latch bolt 8 is retracted to release the door, the latter is automatically thrown open by the pressure of the spring-backed button against the car body.

When the door 6 is closed, the spring 21 75 is compressed as the button 20 contacts with the car body 5 and is thereby pushed back into the housing 22. It will, therefore, be evident that when the latch bolt 8 is retracted to release the door, the latter is automatically thrown open by the pressure of the spring-backed button against the car body.

The device is simple in construction and efficient in operation, and it is also reversible 80 so that it can be applied to either a right or left-hand door.

I claim:

The combination with a door, of a spring-actuated bolt carried thereby and having a 85 notch, a hand operated lever carried by said door and extending into said notch for controlling said bolt, said bolt being provided with a recess, a second lever carried by said door and received in said recess of the bolt, 90 the lower portion of said door being provided with an arcuate slot, and a laterally projecting foot engaged portion carried by said second lever and extending through said arcuate slot whereby the same may be 95 operated from one side of the door and at a point adjacent the lower end of the door.

In testimony whereof I affix my signature.

CHARLES W. PAGE.
